CHARGING VALVE IN REFRIGERATION APPARATUS

Edward M. May, Detroit, Mich., assignor to Meco-Pilot Manufacturing Company, Detroit, Mich., a corporation of Michigan

Application January 6, 1950, Serial No. 137,075

13 Claims. (Cl. 62—115)

1

This invention relates to refrigeration apparatus of the closed circuit compressor-condenser-expander type and particularly to such apparatus in which the motor-driven compressor is hermetically enclosed, either partially or completely, and expansion of the refrigerant is effected through a restricted passage of fixed capacity, such, for example as a capillary tube.

In refrigeration apparatus of the character specified means have been provided for the purpose of facilitating the evacuation of air and moisture from the interior of the system and charging in of refrigerant and lubricating oil; and in the case of systems having capillary expansion means the compressor unit has been provided with a valved fitting permitting the simultaneous connection of both the high and low sides of the system with the evacuating pump so that a minimum amount of gas or vapor need be drawn through the capillary expander. In this way the time of evacuating and charging and the cost thereof are substantially reduced.

It is an object of the present invention to provide a refrigeration apparatus of the character specified having means for facilitating the evacuating and charging of the system that are very simple structurally, susceptible of manufacture at low cost, adaptable to compressor units varying in construction and susceptible, in use, of easy and rapid manipulation.

With the stated object in view the invention consists in certain novel forms of valve and conduit devices and combinations thereof with compressor means which will be set forth and explained, in the course of the following description of specific preferred embodiments shown in the accompanying drawings, and then particularly pointed out in appended claims.

In the drawings,

Fig. 1 is a view of a refrigeration system embodying the invention and illustrating the manner of use thereof to effect evacuation and charging of the system, some parts of the system being shown diagrammatically and others in cross section.

Fig. 2 is an enlarged detached view in axial section of the evacuating and charging valve device included in Fig. 1 but with the valve elements closed as in normal operation of the system.

Figs. 3 and 4 are, respectively, left end and right end elevations of the valve shown in Fig. 2.

Fig. 5 is a face view of the sheet metal stamping constituting, when bent, to form, the valve-retaining clip of the valve device.

2

Fig. 6 is a view similar to Fig. 1 showing an embodiment of the invention in a refrigerating system in which the hermetically closed chamber in which the compressor is enclosed constitutes a part of the high side of the system.

Fig. 7 is an axial sectional view of a modified form of charging and evacuating valve device for use in a system like that shown in Fig. 1, the modified device being constructed to permit evacuation of the system either by separate vacuum pump or by the refrigerant compressor thereof.

Fig. 8 is another axial sectional view of the fitting shown in Fig. 7 with the valves thereof in the positions they occupy during evacuation.

Referring in detail to the constructions illustrated, and first to that shown in Figs. 1-5 inclusive, 1 generally designates a motor-driven compressor unit comprising a compressor 2, having intake and discharge ports at 3 and 4, respectively, and having a casing or dome structure 5 which hermetically encloses the compressor, in accordance with familiar practice, with the intake port 3 of the compressor in communication with the interior chamber of the dome.

A valve fitting generally designated by the numeral 6 has a chambered body structure comprising a main part 7 and a threaded nipple 8 tightly secured, as by brazing, in a recess of part 7. The body structure has one end secured in an aperture in the dome 5 with a joint rendered hermetically tight by brazing. The body part 7 is formed with an interior chamber 9 disposed between oppositely facing valve seats 10 and 11 formed in one with the body.

A passage 12 extends through nipple 8 and opens freely into chamber 9. A second passage 13 can communicate through valve seat 10 with chamber 9 and is in open communication with the interior of the casing or dome part of the compressor unit.

A third passage 14 of body 7 can communicate with chamber 9 through valve seat 11 and can open into the atmosphere or be connected with other apparatus.

Communication between the chamber of the dome 5 and the valve body chamber 9 through passage 13 is controlled by a valve 15 which cooperates with the seat 10. This valve is formed with an axial passage 16 which communicates through lateral passages 17 with chamber 9. A flexible metal tube 18 has one end hermetically connected to passage 16 of valve 15 while its other end is similarly connected to the outlet port 4 of the compressor. Tube 18 has a measure

of elastic flexibility which permits endwise movement of valve 15 relative to seat 10. The inner end of valve member 15 is formed with a circumferential ridge 15a to support the inner end of the valve in approximate axial alignment with the outer end. The valve 15 has its inner end threaded internally to cooperate with the threaded stem of a valve 19 which is disposed in passage 14 to cooperate with the valve seat 11. Valve 19 is formed with a socket 19a to receive a wrench. By clock-wise rotation of valve 19, valve 15 being held against rotation by tube 18, the two valves 15 and 19 can be drawn together to close them on their oppositely facing seats 10 and 11, while rotation of valve 19 in the opposite direction serves to open the valves. The end of valve body 7 which projects into the chamber of dome 5 is fitted with a detachable spring clip 20. This clip has a pair of arms 20a which engage a circumferential groove 7a in body 7 and yieldingly secure the clip to the body. The clip also has arms 20b which embrace tube 18 and, when the valves are opened, serve as a resilient abutment that opposes movement of valve 15 from passage 13 and thus insures the opening of valve 19. Clip 20, being yieldingly secured on body 7, can readily be detached from it to permit removal of the valve 15 from the body should there be occasion to do so before the dome is finally sealed in the process of manufacture.

The passage 12 of the valve body structure is connected by a tube 21 with a condenser 22 which in turn is connected with a capillary tube expander 23. The capillary tube is connected to an evaporator 24 which in turn communicates through tube 25 with the interior of dome 5. Thus it will be seen that the valve fitting 6 is interposed in the high side of the refrigeration system between the compressor and the condenser.

In the preparation of such a refrigeration system for use it is customary to evacuate the interior of the system by suitable suction means such as a vacuum pump and then introduce the charge of refrigerant and lubricating oil. To accomplish this with the apparatus which has been described a packed wrench of well-known form designated generally by the numeral 26 can be connected to the body 7 of the valve fitting as shown in Fig. 1. Such wrench comprises a chambered body 27 fitted with a coupling 28 by which the body 27 can be tightly connected to the end of the body 7 with passage 14 of the latter in communication with the interior chamber of the wrench. The wrench spindle 29 is formed to engage the socket of valve 19 when the wrench spindle is manually pressed towards the valve. The wrench body 27 is fitted with conduit means 30 by which the wrench chamber can be connected to evacuating and charging equipment.

It will be observed that when the two valves 15 and 19 are opened by rotation of valve 19 all parts of both the high side and the low side of the refrigeration system are placed in open communication with the chamber 9 of the valve fitting so that the gas or vapor contents of the entire system can readily be evacuated through passage 14 of the valve fitting without the time consuming operation of drawing a large part of such contents through the capillary expansion coil.

In evacuating the system, when the wrench 26 has been connected to the valve device and

to evacuating means, the valves 15 and 19, if closed, as shown in Fig. 2, are opened by counter-clockwise rotation of valve 19. The resultant opening movements of the two valves will depend upon the condition of tube 18. When the compressor unit and valve device parts are assembled it may happen that the natural unstressed position of resiliently flexible tube 18 is such as to press valve 15 against its seat, or instead it may tend to draw the valve away from its seat. In the first case rotation of valve 19 will move it away from its seat until its right end engages the end of wrench body 27 (the position shown in Fig. 1). Then axial movement of valve 19 will stop and valve 15 will be opened against any resistance exerted by tube 18. When valve 15 has opened to the position shown in Fig. 1 the clip 20 will oppose further opening movement, but it will bend (while offering increasing resistance) until the threads of the two valves disengage, thus limiting the opening movement if the operator has not previously stopped it. On later clockwise rotation of valve 19 to close the valves, clip 20 will restore valve 15 to the position shown in Fig. 1 so it can be engaged by the threads of valve 19.

If, in assembly of the apparatus, it chances that tube 18 exerts a pull on valve 15 away from its seat (the second case above mentioned), the effect, on opening of the valves by rotation of valve 19, will be that valve 15 will open first and move into engagement with clip 20, whereupon the valve 19 will open until its transverse cylindrical end surface engages wrench body 27. Thereafter if valve 19 is further rotated the action will be the same as in the first case.

Following evacuation of the system the conduit means 30 may be connected in turn with sources of refrigerant and lubricant to charge the system. Thereafter, valves 15 and 19 are closed and wrench detached, whereupon passage 14 of the valve device may be closed by screw cap (as indicated by dashed lines in Fig. 2) to keep the passage free of dust or other foreign materials.

It will be apparent that the valve device is compact, of simple construction and easy to manufacture. The assembly of the valve device with the compressor unit is rendered easy by the fact that tube 18 is not required to position valve 15 in any specific position to insure correct operation of the valve device. Also the apparatus is extremely easy to manipulate to carry out the evacuating and charging operations because one of the two valves is automatically actuated by the operation of the other and no special skill is required. Since the tube 18 which connects the port of the compressor with the valve member 15 may take a variety of forms, the valve fitting can readily be adapted to a variety of compressor designs.

Fig. 6 shows the application of the invention to a system in which the valve fitting for effecting evacuation and charging of the system is interposed in the low side of the system. In this construction the compressor unit 31 comprises a compressor 32 having its discharge port 33 opening into the chamber of dome 34 of the unit. This chamber is connected through conduit 35 with condenser 36 which in turn is connected with capillary coil 37 through which refrigerant is expanded into the evaporator 38. The evaporator is in turn connected by conduit 39 with a valve device 40 which is identical in construction with the device 6 shown in Fig.

1 of the drawing so that the foregoing description of the device 6 will serve for the valve device 40. However in this second form of construction the valve controlling communication between the dome chamber and the inner chamber of the valve device 40 is connected by flexible tube 41 with the suction port of the compressor. As in the case of Fig. 1 the arrows indicate the direction of flow through the various parts of the system.

It will be apparent without further explanation that in the system shown in Fig. 6 the valve device can be actuated by a packed wrench fitting such as that shown in Fig. 1 to effect evacuation and charging of the system in the manner already described.

The form of valve fitting shown in Figs. 7 and 8 of the drawings is similar in construction to the valve fittings which have been described but presents a modification of the latter which adapts the invention for use when it is desired to make use of the refrigeration compressor to effect evacuation of the system.

In the modified construction the valve fitting 42 comprises a body structure made up of a main member 43, a nipple 44, tubular member 45 threaded into one end of main member 43 and a tubular member 46 in the opposite end of member 43, the nipple 44 and tubular member 46 being connected by brazing to the main member.

The body structure has an interior chamber 47 with which passage 48 through nipple 44 is in free communication. Passage 49 through tubular member 45 communicates through valve seat 45a with chamber 47 and is at all time freely open to the interior of the compressor dome 5, to which member 43 is connected by brazing. The passage 50 through tubular member 46 communicates through valve seat 46a with chamber 47.

A valve 51 disposed partly in chamber 47 and partly in passage 49 is formed to engage valve seat 45a and has an axial passage 52 and branch passages 53 that open into chamber 47. The tube 18 of the apparatus is hermetically connected to the passage 52 of valve 51. As in the first-described construction, tube 18 prevents rotation of valve 51 but has an elastic flexibility that permits the required axial movement of the valve. However, in the present construction the tube is formed and assembled so as to exert on valve 51 a tension (represented in Figs. 7 and 8 by arrow T) that holds the valve yieldingly in contact with the seat 45a.

Valve 51 is formed to cooperate also with a seat 43a which is formed on the body member 43 and located between passage 48 and passage 50. The valve 51 if further formed with internal threads to engage the threaded stem of a valve 54 which is disposed in chamber 47 to cooperate with seat 46a and control communication between said chamber and passage 50. The valve body 43 is provided internally with a collar 43b surrounding valve 54 in position to be engaged by the shoulder of said valve. However the valve shoulder is formed with a transverse cylindrical surface that provides diametrically opposite passages 54a so that engagement of the valve shoulder with collar 43b does not stop flow past the collar.

Valve 54 is formed with a wrench socket and by rotation of the said valve in a counter-clockwise direction valves 51 and 54 may be forced against their respective seats 45a and 46a, as shown in Fig. 7 which represents the positions of

the valves for normal operation of the refrigeration system. By rotation of valve 54 in a clockwise direction said valve will first be unseated (by reason of the aforementioned tension of tube 18) and then when the valve engages collar 43b valve 51 will be withdrawn from seat 45a. If it is desired to evacuate and charge the system in the manner and by the means described in connection with Fig. 1 and Fig. 6, the described opening movement of valve 51 will be terminated before the valve engages seat 43a, and evacuation means connected to passage 50 will then be in communication with the refrigeration system on both sides of the capillary expander. However, if it is desired to evacuate the system by means of the compressor thereof it is only necessary to open the valve 51 until it closes on seat 43a. This places the chamber of dome 5 in free communication with both the high and low sides of the system. Hence operation of the compressor will draw the contents of both sides of the system into the dome chamber and discharge them through tube 18 and valve fitting 42 to the atmosphere. Thus evacuation of the system is effected except for tube 18 and part of valve chamber 47. This very small part of the system can be quickly purged (after charging with refrigerant) by momentarily opening valve 54.

It is to be understood that the constructions disclosed herein are exemplary and not to be taken as defining the scope of the invention, as it may be embodied in other mechanically equivalent forms within the bounds of the following claims.

What is claimed is:

- 35 1. In refrigeration apparatus, the combination of a compressor unit comprising a compressor with inlet and discharge ports for refrigerant and a casing hermetically enclosing at least a portion of the compressor including the said ports thereof; a valve device comprising a body structure hermetically connected to an apertured part of the compressor unit casing, said body having an interior chamber, a passage for connecting said chamber with one of the high and low sides of a refrigeration system, a second passage with associated valve seat for connecting said chamber with the interior of the compressor unit casing, a third passage with associated valve seat extending from the said chamber to the exterior of the valve device body, a valve for the second passage arranged to cooperate with the seat thereof to control flow therethrough between the interior of the compressor unit casing and the chamber of the valve device body, said valve having a part exposed to the interior of the compressor unit casing and being formed with a passage extending through said exposed part and opening into the said chamber of the valve device body, a valve for the third passage arranged to cooperate with the seat thereof, and means for moving the valves relative to their seats; and a conduit hermetically connected at one end to one of the compressor ports and nonrotatably and hermetically connected at its other end to the passage through the valve of the second passage of the valve device body, said conduit being constructed to permit opening and closing movements of the valve to which it is connected.
- 40 2. Apparatus as claimed in claim 1 in which the second and third passages of the valve device body and the two valves controlling them are mutually aligned axially and the means for moving the two valves comprise screw threads thereon mutually connecting the valves together,
- 45
- 50
- 55
- 60
- 65

70

whereby both valves can be manually operated by rotation of the valve controlling the third passage.

3. Apparatus as claimed in claim 2 in which one of the two valves is constructed to cooperate with the valve device body, when the second and third passages are open, to stop communication between the first and third passages of the said body while permitting communication between the first and second passages and between the said conduit and the third passage.

4. Apparatus as claimed in claim 1 in which one of the two valves is constructed to cooperate with the valve device body, when the second and third passages are open, to stop communication between the first and third passages of the said body while permitting communication between the first and second passages and between the said conduit and the third passage.

5. Apparatus as claimed in claim 1 in which the second and third passages of the valve device body and the two valves controlling them are mutually aligned axially, with the valves constructed to close in opposite directions, and the means for moving the two valves comprise screw threads thereon mutually connecting the valves together, whereby both valves can be manually operated by rotation of the valve controlling the third passage.

6. Apparatus as claimed in claim 1 with the conduit interposed between the compressor and the valve device connected to the discharge port of the compressor.

7. Apparatus as claimed in claim 1 with the conduit interposed between the compressor and the valve device connected to the intake port of the compressor.

8. In closed circuit refrigeration apparatus, the combination of a valve device body structure having an interior chamber, a first passage in free communication with said chamber and leading to the exterior of the body, a second passage with associated valve seat in communication with the interior chamber and leading to the exterior of the body and a third passage with associated valve seat also in communication with the interior chamber and leading to the exterior of the body; a valve for the second passage of the body structure arranged to cooperate with the seat thereof to control flow between the valve and the wall of the passage, said valve being exposed through the second passage to the exterior of the valve body and being formed with a passage opening at one end through the exposed part of the valve for hermetic connection to an end of a conduit disposed outside the valve body and opening at its other end into the interior chamber of the valve body; a valve arranged to cooperate with the seat of the third passage to control flow therethrough; and manually operable

means for moving the valves relative to their seats.

9. Apparatus as claimed in claim 8 in which the manually operable means for moving the two valves operatively interconnects them and acts to hold them in open positions simultaneously and, alternatively, in closed positions simultaneously.

10. Apparatus as claimed in claim 9 in which the valve for the third passage is accessible through said passage and formed to receive a separable exterior operating tool.

11. Apparatus as claimed in claim 8 in which the second and third passages of the valve device body and the two valves controlling them are mutually aligned axially and the means for moving the two valves comprise screw threads thereon mutually connecting the valves together, whereby both valves can be manually operated by rotation of the valve controlling the third passage.

12. Apparatus as claimed in claim 8 in which the second and third passages of the valve device body and the two valves controlling them are mutually aligned axially with the valves constructed to close in opposite directions and the means for moving the two valves comprise screw threads thereon mutually connecting the valves together, whereby both valves can be manually operated by rotation of the valve controlling the third passage.

13. Apparatus as claimed in claim 8 in which the two valves are constructed to cooperate with the valve device body, when the second and third passages are open, to stop communication between the first and third passages of the said body while permitting communication between the first and second passages and between the passage through the valve of the second passage and the third passage.
